Primary Examiner — Michael A Maharajh*(74) Attorney, Agent, or Firm* — Dunlap Bennett & Ludwig, PLLC(57) **CLAIM**

The ornamental design for a massage device, as shown and described.

DESCRIPTION

FIG. 1 is a top perspective view of a massage device, showing my new design;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The dash-dash evenly sized broken lines shown in the drawings depict portions of the massage device that form no part of the claimed design. The dot-dash unevenly sized broken lines shown in the drawings depict the bounds of the massage device that form no part of the claimed design.
